UNITED STATES PATENT OFFICE.

HAROLD S. BEALS, OF SPRINGFIELD, MASSACHUSETTS, ASSIGNOR OF ONE-HALF TO
WILLIAM H. SHEPHERD, OF SPRINGFIELD, MASSACHUSETTS.

SKATE.

Application filed April 5, 1922. Serial No. 549,761.

To all whom it may concern:

Be it known that I, HAROLD S. BEALS, a citizen of the United States, residing at Springfield, in the county of Hampden and State of Massachusetts, have invented new and useful Improvements in Skates, of which the following is a specification.

The present invention relates to improvements in skates and has for its object to provide improved means whereby ice blades or runners of different types may be interchangeably attached to the foot plate of the skate or whereby the skate may be readily converted into a roller skate.

The invention consists in the novel features of construction and the combinations and arrangements of parts hereinafter described and particularly pointed out in the appended claims.

In the accompanying drawings,—

Fig. 1 is a view, in side elevation, of a skate constructed in accordance with the present invention;

Fig. 2 is a perspective view of a portion of the runner shown in Fig. 1; and

Figs. 3 and 4 are detail sectional views taken along the lines 3—3 and 4—4, respectively, of Fig. 1.

Referring to the drawings, the footplate of the improved skate comprises a heel plate 5 and a toe plate 6. The heel and toe plates 5 and 6 are connected, in spaced-apart relation, by means of a girder 7. As shown, the girder 7 extends beneath the foot plate and is spaced therefrom by means of short upright posts 8 and 9 which rise from the points adjacent the opposite ends of the girder, the post 8 being rigidly secured to the forward portion of the heel plate while the post 9 is rigidly secured to the rear portion of the toe plate. As shown in Fig. 4 the girder 7 is U-shaped in cross-section to provide a channel 10 to receive the upper edge portion of a blade or runner such as that shown at 12 in Fig. 1. The runner 12 is constructed with two upwardly extending projections 14 and 15, the projection 14 being adapted to extend between a pair of coupling ears or brackets 16 depending from the rear of the heel plate 5, while the projection 15 is adapted to extend between a similar pair of coupling ears or brackets 17 depending from the forward portion of the toe plate 6. The projections 14 and 15 and the ears 16 and 17 are apertured to re-

ceive bolts 18 which are provided with suitable nuts 19, said bolts and nuts serving to secure the runner projections 14 and 15 detachably to the respective pairs of coupling ears 16 and 17. The upper edge face of the runner 12 is provided with a wide notch 20 to receive the connecting web portion of the channel-shaped girder 7, this notched construction affording a depressed surface 21 for supporting the girder and opposed shoulders 22 for engaging the opposite ends of said web portion of the girder. The shoulders 22 serve to locate the runner 12 relatively to the foot plate so that the apertures in the runner projections 14 and 15 will register with the apertures in the respective pairs of coupling ears or brackets 16 and 17 to receive the bolts 18. The shoulders 22 also serve to prevent end play of the runner relatively to the foot plate when said runner and footplate have been detachably secured together.

To more firmly and rigidly secure the runner to the foot plate, the runner is provided with a screw-threaded stud 24 which rises from the depressed upper face 21 of the runner and is adapted to project through an aperture in the connecting web portion of the channel-shaped girder 7, and a nut 25 is screwed upon the free end of said stud to clamp the girder securely but detachably to the runner.

The foot plate may be provided with clamping jaws 26 and 27 which may be adjustable into engagement with a shoe heel and sole, respectively, as is customary in skate construction. The coupling ears or brackets 16 and 17 may be conveniently struck up from the body of the heel and toe plates or they may be brazed or otherwise secured thereto in any suitable manner. The posts 8 and 9 may be secured to the girder 7 and to the respective heel and toe plates in any suitable manner or they may be formed integrally with said girder or with said heel and toe plates.

The above described girder construction serves to brace or reinforce the heel and toe plates by preventing bending or buckling of the same under the strains to which they are subjected while in use. By virtue of the inverted U-shaped cross-sectional structure of the girder 7, side flanges are provided which overlap and closely embrace the runner and serve to prevent sidewise or tilting

displacement thereof. By means of the nut 25, the runner is rigidly secured to the girder to prevent any possibility of the girder springing upwardly away from the runner.

5 It will be seen that with the above described construction and arrangement of parts the foot plate and runner may be as firmly and rigidly secured together as if the latter were permanently attached to the former.

10 A plurality of ice blades or runners of different types or styles may be provided and adapted to be interchangeably assembled with the foot plate to adapt the skate for use in different kinds of skating such 15 as for racing, hockey playing, or fancy skating.

The invention further contemplates the assembly with the foot-plate and girder above described, of a roller truck (not 20 shown) thereby converting the skate into a roller skate. Obviously the truck may be constructed in the form of a beam of the thickness of the illustrated runner 12, said beam having a notched upper edge portion 25 corresponding to notched portion 20 of said runner for receiving the girder, a screw-threaded stud, corresponding to the stud 25, and apertured projections, corresponding to the projections 14 and 15, for enabling said 30 beam to be detachably secured to the guide and foot-plate.

The invention has been disclosed herein for illustrative purposes in an embodiment at present preferred but it is to be understood that the scope of the invention is defined by the appended claims rather than by the foregoing description.

1. In a skate, the combination with a heel plate and a toe plate and one of a plurality of runners of different types adapted 40 to be interchangeably assembled with the heel and toe plates, of a girder connecting and integral with the heel and toe plates and having a longitudinal channel to receive the upper edge of the runner, and separate means for detachably securing the runner to the heel plate and to the toe plate.

2. In a skate, the combination with a heel 50 plate and a toe plate and one of a plurality of runners of different types adapted to be interchangeably assembled with the heel and toe plates, of a girder rigidly connecting the proximate ends of the heel and toe plates and having a longitudinal channel to receive the upper edge of the runner, means

for detachably securing the runner to said girder, and separate means for detachably securing the runner to the heel plate and to the toe plate.

3. In a skate, the combination with a heel and toe plate and one of a plurality of runners of different types each having spaced shoulders in its upper edge and adapted to be interchangeably assembled with the heel and toe plates, of a girder connecting and integral with the heel and toe plates and having a longitudinal channel to engage the upper edge of a runner between the shoulders thereof to locate the said heel and toe plate relative to the runner, means for clamping the said runner and toe plate rigidly together, means for detachably securing the heel plate and toe plate to the runner.

4. In a skate, the combination with a heel plate and a toe plate and one of a plurality of runners of different types each having spaced shoulders in its upper edge and adapted to be interchangeably assembled with the heel and toe plates, of a support depending from the forward portion of the heel plate, a support depending from the rear portion of the toe-plate, a channel-shaped girder rigidly connecting the lower extremities of said supports and arranged to receive and rest upon the middle portion of said runner between the shoulders thereof, a stud rising from said runner and extending through said girder between said supports, a nut threaded upon said stud above said girder for securing the runner to the latter, and means for detachably securing said runner to the rear of the heel plate and to the forward portion of the toe plate.

5. In a skate, the combination with a heel plate and a toe plate and one of a plurality of runners of different types adapted to be interchangeably assembled with the heel and toe plates, of coupling brackets at the rear of the heel plate and at the front of the toe plate, means for detachably securing said runner to said brackets, and means integral with the heel and toe plate detachably secured to said runner for supporting the forward portion of the heel plate and the rear portion of the toe plate.

In testimony whereof I have affixed my signature.

HAROLD S. BEALS.
